UNITED STATES PATENT OFFICE.

FRED LARRENCE, OF OAKHURST, NEW JERSEY.

SAND BOX FOR GOLF COURSES.

Application filed May 20, 1925. Serial No. 31,591.

To all whom it may concern:

Be it known that I, FRED LARRENCE, a citizen of the United States, and resident of Oakhurst, in the county of Monmouth and State of New Jersey, have invented certain new and useful Improvements in Sand Boxes for Golf Courses, of which the following is a specification.

My invention relates to a sand box such as is sometimes termed a tee-box for containing a supply of sand and also a separate supply of water whereby the sand may be moistened and a proper tee constructed.

An object of the invention is to construct such a box and support therefor which shall be simple and efficient in construction but durable, and wherein provision is made for a cover to the box which will not interfere with the ready access thereto but will afford substantial protection therefor.

A further object of the invention is to provide holding means for the box whereby the box and holding means can be readily removed together from the support or the box itself may be readily removed from the holding means.

Further objects of the invention will be apparent from the following detailed description and the appended claims.

In the drawings:

Figure 1 is an end elevation of my invention.

Figure 2 is a side elevation of the same.

Figure 3 is a vertical section on the line 3—3 of Figure 2.

Figure 4 is a horizontal section on the line 4—4 of Figure 2.

Figure 5 is a perspective view of the means for supporting the box upon the main support.

The invention comprises a frame, including four vertical posts 1 supported at their lower ends in metal plates or concrete setting or in any other desired manner. At their upper ends these boxes enter T couplings 2, which also support the ends of side rods 3 and end rods 4. The couplings 2 also receive the lower ends of rods 5 which support similar couplings 6 at their upper ends and these couplings receive the ends of side rods 7 and end rods 8. Intermediate the ends of the rods 8 are T couplings 9 in which are supported the lower ends of rods 10 connected at their upper end to a longitudinal rod 11 which is parallel to the side rods 3

and 7 of the frame. Suitable cap pieces 12 are fast to the top of the coupling 6.

This framework as illustrated, is constructed of tubing although other forms of metal framework may be employed. This construction gives a very strong and relatively light support which can be rendered ornamental in appearance as desired.

From the longitudinal side rods 7 are supported boxes for holding sand and water, the sand box being preferably considerably larger than the water box. For supporting the sand box there is provided a pair of U-shaped members having sides 13 and a connecting bottom piece 14. The sides 13 terminate at their upper extremities in hooked ends 15 which fit over the frame bars 7. Two longitudinal bars 16 are fastened to the bottom portions 14 of the supporting members by rivets 17 or in any other suitable manner. These bars extend in each direction slightly beyond the cross pieces 14 of the supporting members and have short upturned ends 18. The container 19 for the sand fits between the vertical sides 13 of the supporting members and between the upturned ends 18 at the opposite ends of the bars 16. It is therefore firmly supported against accidental movement or displacement but can be lifted out as desired. It is also possible to remove the box and supporting framework together.

The supporting means for the water box is of similar character comprising U-shaped members having vertical side portions 21 terminating in hooks 22 which hook over the side bars 7. Bottom cross pieces 23 are fast to these members and terminate at their ends in upwardly projecting portions 24. A receptacle 25 for the water fits between the vertical portion 21 and the upturned ends 24.

A cover is provided which is composed of two side pieces 26 arranged at substantially right angles to each other and end pieces 27, the whole forming a substantially trough shaped member. The end pieces 27 have openings immediately adjacent the apex of the angle formed by the joining of the side pieces 26 and the rod 11 passes therethrough when the parts are assembled. The cover is therefore supported to swing freely on the rod 11 to either side as may be desired. It is obviously made of a length to fit within the vertical members 10 but is long enough to overhang beyond the sand box and the

water box. Whenever access to either of these boxes is desired, the cover is simply rotated from the full to the dotted line position of Figure 3.

- 5 It will be evident that the invention provides a strong and simple construction for the support of sand and water boxes and the protection of the sand within the box. The device may be made ornamental in appearance and when constructed of metal tubing can be transported readily from one place to another. Either of the containers can be removed independently of their supporting frame or with said frame. Obviously various detail changes can be made in the precise construction without departing in any way from the spirit of the invention, which is to be regarded as limited only by the scope of the appended claims.
- 10 20 I claim as my invention:
1. A sand box for golf courses comprising an open framework having longitudinal side bars, generally U-shaped members having free hooked ends to engage over said side bars, base pieces attached to the bottom of the U-shaped members and extending longitudinally, and a container supported by the U-shaped members and the base pieces, said base pieces having upturned ends between which the ends of the container fit.
  2. A sand box for golf courses comprising an open framework having longitudinal side bars, central end posts supported by said framework, a removable support for a container carried by said longitudinal bars, and a cover for the container carried by said posts.
  3. A sand box for golf courses comprising an open framework having longitudinal side bars, central end posts supported by said framework, a removable support for a container carried by said longitudinal bars, and a cover for the container carried by said posts.
  4. A sand box for golf courses comprising an open framework having longitudinal side bars, central end posts supported by said framework, a removable support for a container carried by said longitudinal bars, and a cover for the container carried by said posts.
  5. A sand box for golf courses comprising an open framework having longitudinal side bars, central end posts supported by said framework, a removable support for a container carried by said longitudinal bars, and a cover for the container carried by said posts.

free hooked ends to engage over said side bars, base pieces attached to the bottom of the U-shaped members and extending longitudinally, and a container supported by the U-shaped members and the base pieces, said base pieces having upturned ends between which the ends of the container fit.

3. A sand box for golf courses comprising an open framework having longitudinal side bars, central end posts supported by said framework, a removable support for a container carried by said longitudinal bars, and a cover for the container carried by said posts.

4. A sand box for golf courses comprising an open framework having longitudinal side bars, central end posts supported by said framework, a removable support for a container carried by said longitudinal bars, and a cover for the container carried by said posts.

5. A sand box for golf courses comprising an open framework having longitudinal side bars, central end posts supported by said framework, a removable support for a container carried by said longitudinal bars, and a cover for the container carried by said posts.

In testimony whereof, I have hereunto subscribed my name.

FRED LARRENCE.
